(57) **CLAIM**

The ornamental design for a floater plate, as shown and described.

DESCRIPTION

FIG. 1 is rear perspective view of a floater plate according to my new design;

FIG. 2 is a rear elevation view thereof;

FIG. 3 is front elevation view thereof;

FIG. 4 is a top plan view thereof;

FIG. 5 is a top cross-sectional view taken along section line A-A of FIG. 3; and,

FIG. 6 is a partial cutaway view of FIG. 3 with a portion thereof removed to show internal features.

The dash-dot line shown in FIG. 3 is a cross-section line that forms no part of the claimed design. The dash-dot lines shown in FIG. 6 show boundaries of the removed portion of the cutaway that form no part of the claimed design.

1 Claim, 6 Drawing Sheets
